UNITED STATES PATENT OFFICE

CARL A. SHEPARD, OF DES MOINES, IOWA

DOOR HINGE AND STOP

Application filed June 4, 1928. Serial No. 282,656.

The object of my invention is to provide a hinge and door stop of simple, durable and inexpensive construction, which may be easily and quickly applied, and when applied will positively and automatically lock the door to which the device is attached in a number of open positions, when the door has been swung to said positions.

A further object is to provide a door stop supported on a hinge member, whereby both devices may be simultaneously applied, and whereby the hinge plates may be made to support the stop mechanism, thus considerably cheapening the construction, and at the same time increasing the rigidity of the device.

A further object is to provide a door stop improved means for locking the door in the desired open position, and in connection therewith means for releasing the locking mechanism.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a front elevation of my improved hinge and stop.

Figure 2 is a top view of same showing the manner in which it is applied to a door and its frame, said door and frame being in section.

Figure 3 is an enlarged detail view of the latching mechanism, a portion of the roller guide being in section.

Figure 4 is a detail sectional view taken on the line 4—4 of Figure 3.

Figure 5 is a detail sectional view taken on the line 5—5 of Figure 3.

My improved device comprises a hinge member formed of plates 10 and 11 pivotally connected together by means of a pin 12 in the usual manner. The outer face of the plate 10 is provided with a pair of angle irons 13 spaced apart a slight distance.

The inner edges of the plates are provided with outwardly extending flanges 14 for receiving a link 15 between them. The

said link has one end connected to the flanges 14 by means of a bolt 16 mounted in suitable openings 17 in the flanges 14.

The hinge plate 11 is provided with a pair of Z-bars 18, said bars having their inner edges provided with laterally extending flanges 19 terminating in inwardly extending flanges 20. The inner edges of the flanges 20 are spaced apart a slight distance for receiving the free end of the link 15 between them, the free end of the link being curved inwardly at 21. The inwardly extending portion has stub shafts 22 on which are mounted rollers 23 designed to travel in the channel formed by the flanges 19 and 20 and adjacent to the outer face of the plate 11.

The link 15 is of such length that when the hinge members 11 are in their closed position when mounted on a door, the rollers 23 will be at the inner end of the channel, as illustrated in Figure 1.

One of the flanges 19 is provided with an opening 24 for receiving a latch device 25 pivotally connected to the plate 11 by means of a rivet 26. The latch 25 has an upwardly projecting arm 27 to which an operating chain 28 is attached, the outer end of which is provided with a loop 29 for receiving the operator's fingers.

The latch member 25 is provided with a downwardly extending portion 30, the inner edge of which is inclined somewhat to the longitudinal axis of the member 25 and provided with an outwardly extending flange 31, said flange being tapered as illustrated in Figure 2. The outer end of the member 30 is beveled at 32 as illustrated in Figure 4, and designed to rest beneath one of the rollers 23 when said rollers are in the outer end of the channel, as illustrated in Figure 3, in such a manner that any inward movement of the roller 23 when the latch is in position will cause the roller 23 to be wedged against one of the flanges 20.

By this arrangement means is provided whereby the said roller is blocked against inward movement, and whereby most of the inward strain is relieved from the pivot 26 of the latch 25, said strain being carried

by the Z-bar 18 which is riveted to the plate 11.

By this arrangement it will be seen that as the hinge member 11 is swung on the pivot 12 toward and from the hinge member 10, the rollers 23 will travel longitudinally in the channel formed by the members 19 and 20, which I shall term a roller guide way.

In actual operation the hinge member 10 may be applied to the door frame or the outside wall of the building, while the hinge member 11 is applied to the door in the usual manner. Said hinge may be applied either at the top or the central portion of the door and used in connection with other hinge members of ordinary construction. In Figures 1 and 2, the plate 10 is illustrated as being applied to the outside wall of a building 34, while the hinge member 11 is applied to the door 35. The chain 28 may be placed in a loop or eyelet 36 near the free edge of the door where it may be easily grasped by the operator.

When the door is swung to an open position, the rollers 23 will travel outwardly causing the latch member to be elevated, on account of the upper one of the rollers engaging the under surface of the inclined flange 31, which will cause the free end of the latch member to be elevated and the roller 23 to pass beneath said flange 31, after which the member 30 will drop in front of the roller 23, as illustrated in Figure 3, and the door automatically locked in the position illustrated in Figure 2.

The angle at which the door 35 is set or locked relative to the wall 34 may be varied by adjusting the bolt 16 in the openings 17.

The rollers 23 are secured against outward movement by engaging a flange 37 bent laterally from the plate 11. The edge of the flange 37 is bent over the ends of the flanges 20 to support the ends of said flanges against movement away from the plate 11. The member 30 is provided with a weight 38 which assists in causing the latch 25 to move to its closed position.

Thus it will be seen that I have provided a combined door hinge and stop adapted to automatically lock a freely swinging door to a predetermined open position and to retain the door in said open position until it has been released by pulling the chain 28 and releasing the latch 25 from the rollers 23. The device is mounted on the hinge plates so that the mounting of the device will be simplified and at the same time the racking strain, due to the wind blowing the open door, will be carried by said plates.

I claim as my invention:

1. In a device of the class described, a pair of hinge plates, a link supported in a plane perpendicular to the pivotal axis of said hinge, means for pivotally connecting one

end of said link to one of said hinge plates, a roller guide supported on the other hinge plate for receiving the free end of said link, a pair of rollers on said link within said guide, said rollers being designed to move longitudinally of said guide as the hinge members are moved toward and from each other, a latch device for automatically locking the rollers to their outer limit of movement as the hinge members are swung toward each other, and means for releasing said latch device, said latch device having a tapered edge adapted to rest between said rollers and said hinge plate to wedge the rollers against said guide.

2. In a device of the class described, a pair of hinge plates, one of said plates having its outer surface provided with a pair of spaced angle irons, the laterally projecting flanges of which are supported adjacent and spaced apart, a link having one end pivotally and adjustably connected to said laterally projecting flanges, the other hinge plate being provided with a pair of spaced Z-bars having outwardly extending flanges terminating in inwardly extending and spaced flanges for receiving the free end of said link between them, the free end of said link having stub shafts, a roller on each of the stub shafts to travel between said inwardly extending flanges and said hinge plate, one of the outwardly extending flanges of said Z-bars having a notch for receiving a latch device having a downwardly extending portion, the outer edge of which is beveled and designed to be supported between one of said rollers and said hinge plate when the roller is at its outer limit of movement and to wedge the rollers against said inwardly extending flanges as said rollers are moved inwardly.

3. In a device of the class described, a pair of hinge plates, one of said plates having its outer surface provided with a pair of spaced angle irons, the laterally projecting flanges of which are supported adjacent and spaced apart, a link having one end pivotally and adjustably connected to said laterally projecting flanges, the other hinge plate being provided with a pair of spaced Z-bars having outwardly extending flanges terminating in inwardly extending and spaced flanges for receiving the free end of said link between them, the free end of said link having stub shafts, a roller on each of the stub shafts to travel between said inwardly extending flanges and said hinge plate, one of the outwardly extending flanges of said Z-bars having a notch for receiving a latch device having a downwardly extending portion, the outer edge of which is beveled and designed to be supported between one of said rollers and said hinge plate when the roller is at its outer limit of movement and to wedge the rollers

against said inwardly extending flanges as said rollers are moved inwardly, means for limiting the outward movement of said rollers, and means for releasing said latch device.

5 4. In a device of the class described, a pair of hinge plates, a link, means for pivotally and adjustably connecting one end of said link to one of said hinge plates, a guide supported on the other hinge plate for receiving the free end of said link, guide members on said link within said guide, said guide members being designed to move longitudinally of said guide as the hinge members are moved toward and from each other, means for limiting the movement of said guide members, a latch device for automatically locking the guide members at their outer limit of movement against lateral and 20 longitudinal movement, said latch device having a tapered edge adapted to rest between one of said guide members and said hinge plate to wedge the guide members against said guide and said limiting means.

25 5. In a device of the class described, a pair of hinge plates, a link supported in a plane perpendicular to the pivot center of said hinge, means for pivotally and adjustably connecting one end of said link to one of said hinge plates, a guide supported on the other hinge plate for receiving the free end of said link, guide members on said link within said guide, said guide members being designed to move longitudinally of said 30 guide as the hinge members are moved toward and from each other, means for limiting the movement of said guide members, a latch device for automatically locking the guide members at their outer limit of movement against lateral and longitudinal movement, said latch device having a tapered edge adapted to rest between said guide members and said hinge plate to wedge the guide members against said guide and said 35 limiting means.

40 45 CARL A. SHEPARD.
